(57) **CLAIM**

The ornamental design for a lamp, as shown and described.

DESCRIPTION

FIG. 1 is a first perspective view of a lamp showing our new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of part 9 in FIG. 1; and,

FIG. 10 is an enlarged view of part 10 in FIG. 2.

The broken line portions are included to show unclaimed subject matter only and form no part of the claimed design.

1 Claim, 10 Drawing Sheets(56)
